(57) CLAIM

The ornamental design for a towel as shown and described.

DESCRIPTION

FIG. 1 is a top view of a towel;
FIG. 2 is a bottom view thereof;

FIG. 3 is a right side perspective view viewed from the top thereof;

FIG. 4 is a left side perspective view viewed from the bottom thereof;

FIG. 5 is a front end perspective view viewed from the top thereof;

FIG. 6 is a front end perspective view viewed from the bottom thereof;

FIG. 7 is a perspective view thereof;

FIG. 8 is a top view of the towel in an alternate configuration with the hood-end folded over showing the stretch band;

FIG. 9 is a bottom view of the towel of FIG. 8 thereof;

FIG. 10 is a right side perspective view viewed from the top of the towel of FIG. 8 thereof;

FIG. 11 is a left side perspective view viewed from the bottom of the towel of FIG. 8 thereof;

FIG. 12 is a front end perspective view viewed from the top of the towel of FIG. 8 thereof;

FIG. 13 is a front end perspective view viewed from the bottom of the towel of FIG. 8 thereof; and,

FIG. 14 is a top side perspective view of the towel of FIG. 8 thereof.

The broken lines form no part of the claimed design. The towel is shown with symbolic breaks in its length and width. The appearance of any portion of the article between the break lines forms no part of the claim design.

1 Claim, 14 Drawing Sheets
